HAND GRENADE

John E. Campbell, Detroit, Mich.

Application May 28, 1941, Serial No. 395,517

1 Claim. (Cl. 102—64)

This invention relates to a hand-grenade.

Hand-grenades as heretofore fabricated have not been arranged so that they could be conveniently transported from place to place by a soldier preparatory to using the same. One of the objects of this invention is that of producing a hand-grenade which can be conveniently and easily handled and transported by a soldier preparatory to using the same. This object is achieved by arranging the hand-grenade so that it can be clipped on to a belt. Thus, a plurality of hand-grenades can be clipped on to a single belt and conveniently worn by a soldier.

This invention also contemplates a hand-grenade which is safe to handle and which has a firing control mechanism very much more simple than those presently used with hand-grenades. This object is achieved by controlling and effecting the firing or exploding of the hand-grenade by a firing pin which normally is held out of firing position but preparatory to firing the hand-grenade is shifted into firing position. The firing pin is actuated by impact whenever the hand-grenade strikes an object after being hurled.

In the drawings:

Fig. 1 is a vertical sectional view through the hand-grenade showing the firing pin in non-firing position.

Fig. 2 is a vertical sectional view 90° from the section shown in Fig. 1 with the firing pin shifted to set or firing position.

Fig. 3 is a section along the line 3—3 of Fig. 1.

Fig. 4 is a perspective view showing the hand-grenades mounted on a belt.

Referring more particularly to the drawings, the body or shell of the hand-grenade is designated 1 and the explosive mixture, including the shot or bullet, is designated 2.

The body of the hand-grenade is provided with a recess 3 having a bridge member 4 arranged to fit over a clip 5 riveted or otherwise mounted on a belt 6. The clip 5 is preferably a spring clip. As shown in Fig. 4, the belt 6 is provided with a plurality of clips 5 each carrying a hand-grenade 1.

The hand-grenade is mounted on the belt by slipping the bridge member 4 over the clip 5. The upper end of the clip 5 is turned inwardly toward the belt 6 so that it interengages the bridge 4 and better retains the hand-grenade on the belt. The grenade can be removed from the belt by simply lifting the grenade upwardly so that the bridge 4 slips off of the clip 5. The belt and grenades can be packed for shipment as a unit. A wide web belt is preferably used as pack-

ing material and one or more belts and grenades are packed in a suitable container for shipment.

The firing of the hand-grenade is controlled by one or more firing pins. By way of description rather than limitation, two firing pins 7 are shown which are fixed on a head 8. The head 8 is rotatably mounted upon post 9 and retained thereon by a cap screw 10 and compression spring 11. The compression spring 11 is positioned over the post 9 between nut 12 which is screwed into the head 8 and the head of the screw 10. The screw 10 has a threaded fit with the post 9. The compression of the spring can be regulated by turning the screw 10 in or out. Lock washer 18 is positioned between the head of the screw 10 and the post 9. The head 8 is provided with opposed notches 13 adapted to receive the fingers of the person grasping the head 8.

The body 1 is provided with a pair of openings 14 and a second pair of openings 15 positioned 90° from the openings 14. Detonating material in the form of a detonating cap in any suitable form, such as the detonating cap 16, is placed in the bottom of each of the openings 15. Openings 15 communicate with the explosive material 2 in the hollow interior of the body 1 through passageways 17. Openings 14 serve merely as retaining sockets for pins 7 when the grenade is in safety or non-firing condition.

The operation of the grenade is as follows: As shown in Fig. 1, the grenade is in non-firing position with pins 7 positioned in openings 14 and retained therein by the spring 11. Preparatory to firing the hand-grenade, head 8 is elevated against the tension of spring 11 and turned 90° and then lowered so that pins 7 now fit into openings 15 above caps 16. The compression of spring 11 is regulated so that but a slight force is exerted on head 8. The primary function of spring 11 is to retain the head in lowered position with pins 7 in openings 14 when it is not desired to explode the hand-grenade and with the pins 7 in openings 15 when it is desired to use the hand-grenade. The spring 11 serves primarily as a means for holding the head 8 and pin 7 in either set or off position and does not function to fire the hand-grenade. After the pins 7 have been set into openings 15, the hand-grenade is now ready to be hurled and preparatory to exploding the same. As soon as the hand-grenade hits an object, the impact will be such that head 8 acts through firing pin 7 to explode caps 16 which in turn through firing passages 17 explode the mixture 2. If head 8 strikes the object, the impact is directly transferred through head 8 and

pin 7 to caps 16. If the body of the shell strikes the object, then the inertia of head 8 or shock transmitted to head 8 causes the pins 7 to strike caps 16 and explode the same and thereby fire the grenade.

Instead of filling the body 1 of the grenade with explosive, it can be filled with any desired gas under pressure such as, tear gas, mustard gas, or the like. In such case the head 8 or the entire grenade would be made of any suitable material which would be shattered by the explosion of the caps 16. The head 8 can be made of a frangible plastic material.

The operation of the head 8 of this modified form of grenade would be the same as above described. When hurled with the head 8 in firing position, Fig. 2, the impact would cause the pin 7 to explode the caps 16. This explosion would break or shatter the head 8 and permit the compressed tear or other gas in the body 1 to flow through passageways 17 and openings 15 to atmosphere. In this form of the invention the caps 16 would be used to close passageways 17 and seal the tear gas within the body 1. After the

caps 16 were detonated, passageway 17 would be opened and the gas would leak by the head 8 to atmosphere in case the head were not shattered. Head 8 and pins 7 preferably have a loose fit in the body of the grenade.

5 I claim:

A grenade comprising a hollow body member adapted to hold an explosive charge, firing means exploding in response to an impact for exploding said explosive charge, a shiftable and rotatable head member for said body member, a post upon which said head is mounted for manual movement axially of said post toward and away from said body and for manual rotation about said post, said post being fixed upon said body, a firing pin carried by said head, and a pair of recesses in said body, one of said recesses adapted to receive the pin when in firing position and the other of said recesses adapted to receive the pin and lock the said head member in non-firing position, and a spring yieldably urging said head toward said body.

JOHN B. CAMPBELL.
